UNITED STATES PATENT OFFICE.

NELSON B. HENRY, OF ATLANTA, GEORGIA, ASSIGNOR TO THE MURRAY COMPANY,
OF DALLAS, TEXAS, A CORPORATION OF TEXAS.

OIL-EXPRESSING CAGE AND PRESS.

1,356,623.

Specification of Letters Patent. Patented Oct. 26, 1920.

Application filed September 9, 1919. Serial No. 322,655.

To all whom it may concern:

Be it known that I, NELSON B. HENRY, a citizen of the United States, residing at Atlanta, in the county of Fulton and State 5 of Georgia, have invented certain new and useful Improvements in Oil-Expressing Cages and Presses, of which the following is a specification.

My invention has relation to oil expressing 10 cages and presses especially adapted for the extraction of oil from cotton seed cake or the like.

My present invention has for its object the provision of a cage adapted for the reception of a plurality of superposed oil 15 cakes, and constructed with a plurality of superposed plates arranged to receive and properly conduct off the oil from the expressed cakes, said cage being so constructed and so arranged with respect to 20 the oil press that the cage with its cakes may be readily inserted in or removed from the press as occasion requires.

The nature and scope of my invention 25 will be more fully understood from the following description, taken in connection with the accompanying drawings forming part hereof, in which—

Figure 1 is a side elevation of a press arranged to receive the cage embodying my 30 invention.

Fig. 2 is a plan view of the base to receive the cage, said base constituting an oil chamber.

Fig. 3 is a plan view of the bottom of the 35 press.

Fig. 4 is a top view of the bottom frame of the cage.

Fig. 5 is a side elevational view of the 40 cage removed from its oil receiving base and from the press.

Fig. 6 is a vertical sectional view illustrating in detail the arrangement and construction of the cage, and

Fig. 7 is a detail perspective view of a portion of one of the plates constituting the cage.

Referring to the drawings, the press has the usual hydraulic piston 1 and cylinder 50 2, and the top block 3 supported from the upper frame 4, the cylinder frame 5 and upper frame 4 being united by the usual standards 6.

On the lower frame 5 is supported the 55 two parallel L beams or angle pieces 10

forming rails for the reception and guidance of the box 7 constituting the base and oil collecting support for the cage. The box 7 has the central ledged aperture 8 for the passage of the piston 1 and the ledge or rim of the aperture supports a follow block 9 adapted to be advanced by the piston into and through the cage, to force the cakes, in said cage, upward against the stationary block 3 of the press. The box 7 has a pipe 65 11 through which oil collecting in its interior may be discharged. The lugs 12 on the box are for a purpose not necessary to explain in the present application for patent. 70

Referring now to Figs. 4 to 7, the cage consists of a plurality of rectangular frames 13 superposed upon each other and assembled between an upper and lower frame 14 and 15 respectively. Each frame 13 is provided with a vertical opening at its corners for the passage of the tying bolts 16. Each frame is also provided with a plurality of apertures 17 vertically disposed, the apertures 17 of all the superposed plates 13 80 forming vertical channels for the passage of oil to the bottom plate 15, which bottom plate (see Fig. 4) has apertures 18 discharging into the box or oil collecting chamber 7. 85

Each frame 13 has adjacent to each set of apertures 17 a horizontal channel 18^a the inner wall of which tapers or is beveled upward to form a lip 19. This lip 19 of one frame 13 forms with the flat base of an adjacent superposed frame 13, or with the base of the uppermost frame 14, a thin opening or slot into the interior of the cage. This thin opening or slot permits of the passage of oil from the pressed cakes 95 into the gradually enlarged channels 18^a and thence into the vertical apertures 17 and to the box 7.

Having thus described the nature and objects of my invention, what I claim as new 100 and desire to secure by Letters Patent is—

1. A press cage made up of a plurality of frames each having a multiplicity of perforations from one side or face of each frame to the other, and a groove around 105 the inner facial margin of the frame reaching from the margin to the perforations; the frames arranged face to face so that said perforations form registering oil conduits traversing the frames and the cage, 110

the grooves, when the frames are fitted together, forming slots between the faces of adjacent frames, leading from the interior of the cage to the registering conduits; 5 means to hold the assembled frames in true relation to form a cage.

2. A press cage made up of a plurality of frames having a multiplicity of perforations from one side or face of each frame 10 to the other registering with the perforations in adjacent frames and having a groove around the inner facial margin of the frame reaching, with gradually increasing depth, from the margin to the perforations; 15 the frames arranged face to face so that said perforations form registering oil

conduits traversing the frames and the cage, the grooves when the frames are fitted together forming slots, expanding inward from the interior of the cage to the register- 20 ing conduits; means to hold the assembled frames in true relation to form a cage.

3. A press cage frame having a multiplicity of perforations from one side or face of each frame to the other and having a 25 groove around the inner facial margin of the frame reaching from the margin to the perforations.

In testimony whereof I have signed my name to this specification.

NELSON B. HENRY.
